BAG FILLING MECHANISM

Walter Mason Ingram, New York, N. Y., assignor
to Millie Patent Holding Co., Inc., New York,
N. Y., a corporation of New York

Application August 6, 1932, Serial No. 627,762

19 Claims. (Cl. 226—61)

The present invention relates to devices for filling receptacles and embodies, more specifically, an improved filling mechanism for use in connection with devices for filling suitable receptacles with tea, coffee and like substances. More particularly, the invention embodies an improved form of receptacle filling mechanism by means of which a substance is fed into a filling device at a predetermined rate, the filling device serving to direct quantities of a substance to suitably placed receptacles in such fashion that the substance is fed to the receptacles only when a receptacle is properly positioned for filling.

Accordingly, an object of the invention is to provide an improved filling mechanism for receptacles, the mechanism being provided with means for supplying a substance in measured quantities to properly positioned receptacles.

A further object of the invention is to provide a filling mechanism wherein means is provided for feeding a substance at a predetermined rate to properly positioned receptacles, the rate of feed being regulated in such fashion that a predetermined quantity of substance is supplied to each receptacle.

A further object of the invention is to provide a filling mechanism wherein a substance is supplied to means for directing the substance to suitably placed receptacles, the directing means being provided with means for automatically preventing the flow of the substance through a filling spout in the event that a receptacle is not properly positioned thereunder.

A further object of the invention is to provide a receptacle support in combination with a filling mechanism whereby means is actuated by the support for controlling the flow of a substance to the support from the filling mechanism.

Further objects, not specifically enumerated above, will be apparent as the invention is described in greater detail in connection with the accompanying drawings, wherein:

Figure 1 is a view in front elevation showing a filling mechanism constructed in accordance with the present invention.

Figure 2 is an enlarged detail plan view showing the device for actuating the filling mechanism.

Figure 3 is an enlarged view in section, showing a portion of the feed chamber and feed mechanism associated therewith, this view being taken on the line 3—3 of Figure 4, and looking in the direction of the arrows.

Figure 4 is a bottom view of the device shown in Figure 3.

Figure 5 is an enlarged view of the driving mechanism for the feeding device shown in Figure 1.

Figure 6 is a view in section, taken on line 6—6 of Figure 5, and looking in the direction of the arrows.

Figure 7 is a view in section, taken on line 7—7 of Figure 1, and looking in the direction of the arrows.

Figure 8 is a view in side elevation, showing the filler mechanism of Figure 1.

Figure 9 is a plan view of a scraper for the feeding mechanism which supplies a substance to the filler mechanism shown in Figures 1 and 8.

Figure 10 is a view in section, taken on line 10—10 of Figure 9, and looking in the direction 10 of the arrows.

Figure 11 is a detail plan view showing a receptacle supporting device and means thereon for controlling the filler mechanism shown in Figure 8.

Figure 12 is a detail view in side elevation showing the elements of the control mechanism of Figure 11.

With reference to the above described figures of the drawings, a rotatable receptacle supporting table is shown at 20, being actuated by a shaft 21 and provided with pairs of receptacle supporting arms 22 and 23, respectively. To receptacles which are supported upon this table, a substance, such as tea, coffee and like substances is supplied by means of a filling mechanism including a filler spout 24, metering device 25, and hopper 26.

The substance is fed to hopper 26 by a feeding mechanism including a feed chamber 27, feeding device 28, and wiper mechanism 29. The feeding mechanism includes a cylindrical chamber 27 having an inturned lower peripheral lip 30 which serves as a stop against which a piston within the chamber abuts to limit the motion thereof. In the form shown, this piston includes plates 31 and 32 between which a flexible diaphragm 33 is secured, the diaphragm being formed with a cylindrical skirt 34 to engage the interior of the cylindrical chamber 27 and form an effective seal thereagainst to prevent substance from passing between the piston and the cylinder. Spaced studs 35 are formed on the piston and are adapted to be received within apertures formed in a plate 36 which is provided with an elongated tube or sleeve 37. The under portion of plate 36 has pivotally mounted thereon levers 38 provided with tabs 39 which are adapted to be engaged by the fingers. Levers 38 are pivotally mounted at 40 and the ends thereof are connected by means of a spring 41 in order that the levers may be urged outwardly against studs 35. In order that the piston may be locked to the plate 36, the studs 35 are formed with recesses 42 within which the levers 38 are received thus releasably mounting the piston on the plate.

The feeding mechanism 28 is actuated by means of a lever 43 which is pivoted at 44 upon a stationary part of the machine and driven by a reciprocated link 45, which constitutes for the feeding mechanism a prime mover having a defi- 60

nite range of movement. A slot 46 is formed on the lever 43 and link 45 is adjustably secured in the slot by means of a nut 47. A suitable scale 48 is formed adjacent the slot to facilitate the proper connection of link 45 to the slot to enable a predetermined movement of the feeding mechanism to be effected upon movement of the arm 43. The end of arm 43 is connected to a rack 49 by means of a link 50, the rack being slidably mounted in a frame 51 and engaging a gear 52 which is rotatably mounted upon a threaded shaft 53. Shaft 53 is journaled in a bracket 54 and provided with a collar 55 to position the same thereon, a collar 56 being provided to properly position gear 52 on the shaft. A ratchet and pawl connection is provided between the gear 52 and shaft 53, this connection including a driving pawl 57, mounted upon gear 52 and urged against a ratchet wheel 58 which is secured to shaft 53. A pivoted dog 59 prevents backward motion of the ratchet wheel with respect to the bracket 54 and thus the reciprocation of rack 49 imparts a step by step uni-directional rotation to threaded shaft 53.

25 Upon sleeve 37, a split nut 60 is formed, this nut engaging the thread of shaft 53 and serving as a clutch between such shaft and sleeve 37. Arms 61 on the nut slidably engage a stationary guide rod 62 to prevent the nut from turning with shaft 53. In this fashion, rotation of shaft 53 imparts an axial motion to sleeve 37 and advances the piston through the chamber 27.

30 As the piston is moved upwardly through the chamber 27 the contents of the chamber are spilled into hopper 26. To insure an even flow of the substance into the hopper a wiper or scraper 29 is provided, Figures 9 and 10 serving to illustrate this construction in detail. The wiper is mounted upon a shaft 63 and is formed 35 with a spiral flange 64 which extends from the central portion of the wiper to the periphery thereof as shown in Figure 9. Shaft 63 is rotated by any suitable mechanism, the speed of rotation thereof being sufficient to impart at least one rotation of the wiper for each fraction of the contents of chamber 27 which is placed in the several receptacles. The wiper 29 is rotated 40 in the direction indicated by the arrow of Figure 9 in order that the flow of the substance from the chamber 27 to the hopper 26 may be sufficiently uniform.

45 With reference to Figures 1, 7, and 8, the filling mechanism will be seen to include telescopically mounted tube portions 65 and 66, tube 65 being mounted upon hopper 26 at the outlet thereof while tube 66 is mounted upon a reciprocating head 67. Head 67 is mounted upon stationary guides 68 and is reciprocated by means of an arm 69 and link 70 which is pivoted at 71 upon the head. The spout 24 is mounted in the head below a chamber 72 which receives substance from the metering device 25 and directs the same into spout 24. In the metering device illustrated herein, a cylindrical drum member 73 is provided 55 with segmental pockets 74 which are adapted to receive substance from tube 66 and, upon rotation in a clockwise direction discharge the substance into chamber 72.

60 Upon counterclockwise rotation of the metering device the substance within the measuring chamber is discharged into a chute 75 which carries the substance away to any suitable receptacle.

65 In order that the substance may be directed 70 into chute 24 only when a receptacle is in proper

position to be filled drum 73 is rotatably mounted upon a shaft 76 and has secured thereto a three sided cam disc 77. In each side a notch 78 is formed, a roller 79 bearing upon the periphery of the disc 77 to engage the notches 78, formed 5 therein and hold the drum 73 in such position that one of the chambers thereof lies under the tube 66. Roller 79 is mounted upon an arm 80 which is pivoted upon a bracket 81 and urged against the disc 77 by means of a spring 82. 10

Upon one end of the drum 73, three pins 83 are mounted, these pins lying between spaced arms 84, upon the ends of which hooks 85 are formed. Arms 84 are mounted upon a carriage 86 which is pivoted on an arm 87. Carriage 86 may thus 15 rock back and forth and is normally urged into the position shown in Figure 8 by means of a spring 88. In the position shown in Figure 8, upon downward movement of head 67, the left hand hook member 85 engages the left hand pin 20 83 and causes the drum to be rotated in a clockwise direction, as viewed in Figures 7 and 8. During such operation, the contents of the chambers of the drum 73 is discharged into chamber 12 and directed to the receptacles positioned 25 below the spout 24. If the head 67 is rocked to the left as viewed in Figure 8, the right hand hook 85 engages the corresponding pin 83 and causes the drum 73 to be rocked in a counter-clockwise direction upon downward movement of 30 head 67. Such movement causes the contents of the drum to be discharged into the chute 75.

The control of drum 73 and head 67 is effected by means of a link 89 which is pivoted to the head 67 at 90 and at 91 to an arm 92 of a bell crank 35 lever. The bell crank lever is pivoted on an arm 93 and connected to a link 94 which is pivoted to one arm of a bell crank lever 95. Bell crank lever 95 is journaled upon a bracket 96 and the other end 102 thereof extends into the position 40 indicated in Figure 12.

Upon the receptacle supporting table 20, levers 97 are pivoted, as at 98. The number of levers 97 equals the number of pairs of arms 22 and 23 mounted thereon. The arms 23 are rigidly secured to table 20 while arms 22 are pivoted thereon at 99. Arms 22 are adapted to engage arms 100 on the levers 97 to cause extensions 101 thereon to be swung upwardly into the path of the arms 102, formed upon levers 95. 50

In operation, a receptacle is placed over supporting fingers which are formed upon arms 22 and 23. This receptacle is indicated at 103 in Figure 11. In such position, the receptacle is adapted to be turned inside out by the filler spout 55 24 as the latter descends during the filling operation. In the event that a receptacle is not properly positioned upon the arms 22 and 23, arm 22 will be urged to the left as viewed in Figures 11 and 12 by means of spring 104 and cause 60 the extension 101 of lever 97 to be moved into the path of arm 102. As the receptacle supporting table is moved into a filling position and in the event that no receptacle is properly placed upon arms 22 and 23, the actuation of arm 65 102 by extension 101 will cause link 94 to be lifted and thus throw hook 85 into the path of the adjacent pin 83 and cause the contents of the drum to be emptied into the spout 75. If the receptacles are properly positioned upon the 70 pairs of arms 22 and 23, the left hand hook 85 will always function to empty the contents of the drum 73 into the chamber 72 and thus effect the filling of the receptacles. In order that varying quantities may be emptied into the respective 75

5 bags, the scale 48 is so calibrated that an indication is given as to what degree of motion of rack 49 is required to divide the contents of chamber 27 into a predetermined number of equal fractional parts. In this manner if only 10 half of the capacity of cylinder 27 is to be utilized and apportioned between a predetermined number of bags or receptacles the connection 47 is so made that the travel of the piston within cylinder 27 is such that the volume within the chamber 27 to be apportioned between a predetermined number of bags is evenly fed to the hopper 26 at such rate as to feed equal fractions of the volume to the predetermined number of 15 receptacles.

It will be seen from the description that the chamber 27 and its connection to the plate 36 affords a means whereby the chamber may be replaced and a properly filled one supplied by moving arms 38 toward each other to disengage the same from notches 42, at which time the cylinder 27 may be lifted off and a new one secured in position.

20 While the invention has been described with specific reference to the accompanying drawings, it is not to be limited, save as defined by the appended claims.

I claim as my invention:

1. A feeding device comprising a chamber 30 forming member in which a substance is adapted to be received, a piston slidably mounted in the chamber, a piston actuating plate formed with an aperture, means to move the plate axially of the chamber, a stud on the piston adapted to be received in the aperture, and means on the plate to secure the stud removably and positively thereto.

2. A feeding device comprising a chamber forming member in which a substance is adapted to be received, a piston slidably mounted in the chamber, means to mount the member removably, a piston actuating plate formed with spaced apertures, means to move the plate axially of the chamber, spaced recessed studs on the piston adapted to be received in the apertures, arms pivoted on the plate and adapted to engage the recesses on the studs, and a spring to urge the arms into engagement with the recesses.

50 3. A feeding device comprising a chamber forming member in which a substance is adapted to be received, means in the chamber for discharging the substance from the top thereof, a rotatable plate at the top of the chamber adjacent the point of discharge therefrom, means to journal the plate on an axis parallel to that of the member and means on the plate to effect a substantially even discharge of the substance from the chamber.

60 4. A feeding device comprising a chamber forming member in which a substance is adapted to be received, means in the chamber for discharging the substance from the top thereof, a rotatable plate at the top of the chamber adjacent the point of discharge therefrom, means to journal the plate eccentrically of the chamber, and a spiral flange on the plate to effect a substantially even discharge of the substance from the chamber.

70 5. A filling device comprising a receptacle supporting member adapted to receive bag-like receptacles to be filled, means to direct a substance to a receptacle, a chambered member to direct substance to the last named means and 75 to a chute selectively, and means actuated by

the supporting device when a bag is supported thereon to actuate the chambered member to direct substance into the means to direct substance into a receptacle, and into the chute when the supporting device has no receptacle 5 supported thereon.

6. A filling device comprising a receptacle supporting member adapted to receive bag-like receptacles to be filled, means to direct a substance to a receptacle, means to move the last named means toward and away from the receptacle supporting member, a chambered member to direct substance to the first directing means, means to supply a substance to the chambered member, and means operable upon movement of the first directing means to cause the chambered member to direct its contents into the first directing means.

7. A filling device comprising a receptacle supporting member adapted to receive bag-like receptacles to be filled, means to direct a substance to a receptacle, means to move the last named means toward and away from the receptacle supporting member, a chambered member to direct substance to the first directing means, means to supply a substance to the chambered member, means operable upon movement of the first directing means to cause the chambered member to direct its contents into the first directing means, and means actuated by the receptacle supporting member to prevent the directing of substance from the chambered member to the first directing means.

8. A filling device comprising a receptacle supporting member adapted to receive bag-like receptacles to be filled, means to direct a substance to a receptacle, means to move the last named means toward and away from the receptacle supporting member, a chambered member to direct substance to the first directing means, means to supply a substance to the chambered member, means operable upon movement of the first directing means to cause the chambered member to direct its contents into the first directing means, and means actuated by the receptacle supporting member when a receptacle is not mounted thereon to prevent the directing of substance from the chambered member to the first directing means.

9. A filling device comprising a receptacle supporting member adapted to receive bag-like receptacles to be filled, means to direct a substance to a receptacle, means to move the last named means toward and away from the receptacle supporting member, a rotatable member having a plurality of chambers journaled on the directing means, means to receive substance from the rotatable member, means actuated by movement of the directing means to turn the rotatable member to discharge the contents thereof into the receiving means, means actuated by movement of the directing means to turn the rotatable member to discharge the contents thereof into the directing means, and means to render operative a selected one of the two last named means.

10. A filling device comprising a receptacle supporting member adapted to receive bag-like receptacles to be filled, means to direct a substance to a receptacle, means to move the last named means toward and away from the receptacle supporting member, a rotatable member having a plurality of chambers journaled on the directing means, means to receive a substance from the rotatable member, means actuated by movement of the directing means to turn the rotatable mem-

ber to discharge the contents thereof into either the receiving means or the directing means, and means to actuate the last named means to cause the contents of the rotatable member to be discharged into either the receiving means or the directing means.

11. A filling device comprising a receptacle supporting member adapted to receive bag-like receptacles to be filled, means to direct a substance 10 to a receptacle, means to move the last named means toward and away from the receptacle supporting member, a rotatable member having a plurality of chambers journaled on the directing means, means to receive substance from the rotatable member, a plurality of pins on the rotatable member, a plate provided with arms adapted to engage selectively the pins, and means to actuate the plate to cause a selected arm to engage one of the pins.

12. A filling device comprising a receptacle supporting member adapted to receive bag-like receptacles to be filled, means to direct a substance 15 to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms adapted to engage selectively the pins, and means to actuate the plate to cause a selected arm to engage one of the pins.

13. A filling device comprising a receptacle 20 supporting member adapted to receive bag-like receptacles to be filled, means to direct a substance to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms 25 adapted to engage selectively the pins, and means to actuate the plate to cause a selected arm to engage one of the pins.

14. A filling device comprising a receptacle supporting member adapted to receive bag-like receptacles to be filled, means to direct a substance 30 to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms 35 spaced upon opposite sides of the axis of the rotatable member and adapted to engage selectively the pins, and means to actuate the plate to cause a selected arm to engage one of the pins.

15. A filling device comprising a receptacle supporting member adapted to receive bag-like receptacles to be filled, means to direct a substance 40 to a receptacle, means to move the last named means toward and away from the receptacle supporting member, a rotatable member having a plurality of chambers journaled on the directing means, means to receive substance from the rotatable member, a plurality of pins spaced 45 in different radii extending from the axis of rotation of the member, a plate provided with arms spaced upon opposite sides of the axis of the rotatable member and adapted to be formed with hooks to engage selectively the pins, and means to actuate the plate to cause a selected arm to engage one of the pins.

16. A filling device comprising a receptacle supporting member adapted to receive bag-like receptacles to be filled, means to direct a substance 50 to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms 55 spaced upon opposite sides of the axis of the rotatable member and adapted to be formed with hooks to engage selectively the pins, and means to rock the plate to move a selected hook into the path of movement of a pin.

17. A filling device comprising a receptacle supporting member adapted to receive bag-like receptacles to be filled, means to direct a substance 60 to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms 65 spaced upon opposite sides of the axis of the rotatable member and adapted to be formed with hooks to engage selectively the pins, and means actuated by the receptacle supporting means to rock the plate to move a selected hook into the path of movement of the pin.

18. A filling device comprising a receptacle supporting member adapted to receive bag-like receptacles to be filled, means to direct a substance 70 to a receptacle, means to move the last named means toward and away from the receptacle supporting member, a rotatable member having a plurality of chambers journaled on the directing means, means to receive substance from the rotatable member, a plurality of pins spaced in different radii extending from the axis of rotation of the member, a plate provided with arms 75 spaced upon opposite sides of the axis of the rotatable member and adapted to be formed with hooks to engage selectively the pins, means to urge the plate into a normal position to cause one of the hooks to lie in the path of one of the pins, and means to rock the plate to move the other hook into the path of movement of another of the pins.

19. A feeding mechanism comprising a chamber forming member in which the substance to be fed may be received, a piston in the chamber for discharging the substance from the top thereof, a prime mover having a definite range of movement, operating connections between the prime mover and the piston, such connections including a system of levers with a variable connection whereby a predetermined movement of the piston can be effected upon movement of the prime mover, and means to effect a substantially even flow of the substance discharged from the chamber.
